CLAIM

We claim the ornamental design for the hitch-coupling tool, as shown and described.

DESCRIPTION

FIG. 1 is a perspective view of the hitch-coupling tool showing our new design;
FIG. 2 is a top view of the hitch-coupling tool;
FIG. 3 is a left-side view of the hitch-coupling tool;
FIG. 4 is a front view of the hitch-coupling tool;
FIG. 5 is a rear view of the hitch-coupling tool;
FIG. 6 is a bottom view of the hitch-coupling tool; and,
FIG. 7 is a right-side view of the hitch-coupling tool.
The broken lines shown in FIGS. 1-7 represent a hitch ball and form no part of the claimed design.
